UNITED STATES PATENT OFFICE.

CHARLES E. BEAN, OF FALL RIVER, MASSACHUSETTS.

DESIGN FOR KNITTED FABRIC.

Specification forming part of Design No. 11,528, dated December 2, 1879; application filed September 15, 1879.
[Term of patent 3½ years.]

To all whom it may concern:

Be it known that I, CHARLES E. BEAN, of Fall River, in the county of Bristol and State of Massachusetts, have originated and designed a Pattern for Knitted Fabric, of which the following is a full, clear, and exact description, reference being had to the accompanying drawing, making part of my specification.

The nature of my design is fully represented in the accompanying drawing, to which reference is made.

The design is applicable to fabric to be used in the manufacture of knitted underwear and other garments, and is shown in the accompanying drawing, wherein A represents a portion of the fabric.

The fabric is knitted with yarns of different colors, preferably one white and one red, or of other color, which colors are produced upon the body of the fabric in waving or zigzag lines of the two colors alternately, and across the fabric are parallel diagonal stripes or lines

a, run in both directions, thus forming diamond-shaped spaces, showing the zigzag lines of alternate colors marked out by the lines of solid color. This gives an ornamental and attractive appearance to the garment.

The colors made use of may be white, blue, brown, or others, and the stripes a may be of any desired width in proportion to the enclosed diamond-shaped spaces.

Having thus described my invention, I claim as new and desire to secure by Letters Patent—

A design for knitted fabrics in which parallel stripes of solid color run diagonally across a body or ground of waving or zigzag lines of alternate colors, forming diamond-shaped spaces on the said body, substantially as described.

CHARLES EDWIN BEAN.
